CLAIM

The ornamental design for a side brush for a cleaning robot, as shown and described.

DESCRIPTION

3.1: Front

3.2: Back

3.3: Left

3.4: Right

3.5: Top

3.6: Bottom

3.7: Perspective

3.8: Perspective

4.1: Front

4.2: Back

4.3: Left

4.4: Right

4.5: Top

4.6: Bottom

4.7: Perspective

4.8: Perspective

Reproductions **3.1** to **3.6** are orthographic projection views

of a side brush for a cleaning robot, and reproductions **3.7**

(Continued)

and **3.8** are perspective views thereof. Reproductions **4.1** to **4.6** are orthographic projection views of a side brush for a cleaning robot, and reproductions **4.7** and **4.8** are perspective views thereof.
